UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,137,277.

Specification of Letters Patent. Patented Apr. 27, 1915.

Application filed February 6, 1913. Serial No. 746,488.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to parts of the platen shift mechanism of visible or front strike typewriting machines in which the platen and carriage are adapted to be folded forward over the keyboard.

One of the principal objects of the invention 15 is to provide simple and effective brackets or devices which may be made from sheet steel or other metal in such a way that the same may be properly secured to the machine frame at the corners thereof and 20 which serve to guide parts of the platen shift mechanism.

Another object of the invention is to provide a typewriting machine having a two-part foldable support, each part comprising 25 a plurality of members on one part of which the carriage is mounted, the other part being connected to the platen shift mechanism, and means whereby the members of one part of the support as well as parts 30 of the platen shift mechanism may be adjusted and held in such adjusted position to permit the members of the two-part support to be properly held relatively to each other in order that the parts may be folded freely 35 and properly.

A further object of the invention is to provide means whereby parts of a foldable support may be quickly adjusted and such means made to form a part of a substantially rectangular and rigid frame in order 40 that the carriage may be uniformly moved and held at opposite sides of the machine when shifted to permit different characters to be printed as is usual in machines of this 45 class.

A still further object of the invention is to provide brackets or guides which may be utilized as supports for other parts of the typewriting machine.

With these and other objects in view, the 50 invention will be hereinafter more particularly described with reference to the accompanying drawings, which form a part of this specification, and will then be pointed out 55 in the claims at the end of the description.

In the drawings, Figure 1 is a fragmentary vertical section of a foldable typewriting machine embodying one form of my invention. Fig. 2 is a fragmentary plan view with the immediate supporting means for 60 the carriage broken away and moved to its folded position. Fig. 3 is an enlarged fragmentary view showing the means whereby the arms of the support and the slides secured thereto may be adjusted. Fig. 4 is 65 a fragmentary detail view of the adjusting and reach rod. Fig. 5 is an enlarged detail perspective view of one of the corner brackets or guides; and Fig. 6 is an enlarged detail perspective view of the other bracket. 70

While the invention is shown as applied more particularly to a machine in which the carriage and its bed may be folded forwardly over the keyboard or otherwise shifted to make the machine more compact when 75 not in use, it will be understood that the invention may be applied equally to a machine that does not fold or is otherwise constructed.

The frame 10 may be of a single piece of 80 aluminum or other sheet metal and has the sides 11 and the rear connecting part or member 12. A rod 13 extends transversely of the machine between the sides 11 and to this rod is held one or more shift levers 14. 85 Only one shift lever 14 is employed though ordinarily in machines of this class two are used to adapt the platen to assume three different positions. The lever 14 is connected to a transversely extending rod 15 90 and this rod is rigidly held at its ends to slides or members 16. There are two slides 16 located on opposite sides of the machine and the upper ends of these slides are rigidly held to the bars or members 17 forming 95 a part of a foldable support 18. A bar or member 19 somewhat longer than the bars 17 is arranged in parallel relation with each of the arms or bars 17 when the machine is in normal working position and at one end 100 is pivoted, as at 20, to the arm 17. The arms or bars 19 have a bed 21 rigidly held thereto and adapted to move along said bed 21 is a carriage 22 in which is mounted a platen 23. The arms with the carriage bed and 105 carriage are adapted to be moved on the pivots 20 forwardly of the machine so that the carriage will be placed in overhanging relation to the keyboard or otherwise according to the length of the arms or mem- 110

bers 19. The parts as thus described may be of the usual or of any preferred construction.

The arms 17 of the support 18 at their inner ends and adjacent to the slides 16 are rigidly held apart by a rod 24. This rod 24 may be solid or tubular, as preferred, and at its ends is provided with threaded openings or recesses 25 and 26. The end having the opening 25 is made so as to abut properly against the inner face of one of the arms 17 and in the same arm 17 is a countersunk opening through which a headed screw 27 passes, the end of which engages the threads of the opening 25 and holds the rod to said arm. The end of the rod 24 having the opening 26 is engaged by the threaded end of a screw 28, the said screw having its head in a countersunk opening in the other arm 17 of the support. An internally threaded sleeve or adjusting member 29 engages the threaded end 30 of the rod 24 and is adjustable lengthwise of the rod, and said sleeve may be rotated on said rod either with the fingers or by inserting a tool in one or more openings 31 provided for that purpose. By this means the rod 24 may be quickly lengthened or shortened without any special fitting of the rod and the arms 19 of the foldable support may be thus spread to adapt the same to be properly positioned relatively to the arms 17 in order that the said arms 19 with the carriage may fold properly.

The end 30 of the rod 24 is slotted lengthwise, as at 32, to intersect the threaded portion. The purpose of this slot is to permit the diameter of the threaded end 30 of the rod to be increased in order to make a very tight fit with the sleeve 29 when the rod is taken from the machine. Thus if occasion arises to take out some of the mechanism, and to do this it becomes necessary to remove the rod 24, the sleeve being tight on the rod would not disturb the adjustment and in reassembling no readjustment of the sleeve 29 would be required.

It will be evident that the slides 16, rod 15 and rod 24, together with the arms 17, form a rigid and substantially rectangular frame, in order that the carriage may have a uniform vertical movement and be properly supported at both sides of the machine.

A bracket or guide 33 is located at one corner of the machine frame and a bracket 34 at the other rear corner of the machine frame. These brackets each have a vertical portion or part 35 with side members or wings 36 arranged at right angles to the vertically arranged portion 35 and above the wings and adapted to be supported thereby is an angular horizontally disposed and overhanging portion 36a.

The brackets may be made of sheet steel or other metal and are first blanked and then bent to the shape shown though said

brackets may be made in any desired way. Each bracket or guide has its vertical portion 35 provided with two threaded openings 37 to receive the threaded ends of the screws 38 to adapt the brackets to be rigidly fastened to the upper portion of the frame member 12 and at the rear corners. One of the wings 36 of each of the brackets is also provided with a threaded opening by which the bracket may be secured by a screw 39 to one of the sides 11 of the frame, thus each bracket is rigidly held in position and serves to brace and hold the members of the frame in position. The horizontal or overhanging portion 36a of the bracket 33 is provided with a round opening 40 and the overhanging portion of the bracket 34 with an elongated opening 41 for the slides 16, otherwise the brackets have substantially the same construction. The elongated opening 41 extends transversely of the machine so that there is no play forwardly or rearwardly for its slide 16 but said slide is permitted to have a lateral or adjusting movement transversely of the machine to permit the rod 24 to properly position the supporting arms 19 in the manner already described. The slides or members 16 are cylindrical at the upper portion thereof where they pass through the openings of the brackets and at their ends where they are secured to the arms 17 may be partly cut away to assist in forming a support for the arms 17 to which they are fastened.

The bed 21 as will be seen rests partly upon the arms 17 and thus the arms 17 and 19 when the machine is in a normal working position are held in parallel relation so that when the slides are moved vertically the arms will both be moved together with the bed, carriage, and platen to the different shifting positions and by reason of the construction the arms 19 may be moved or shifted relatively to the arms 17 to make the machine more compact for transportation or other purposes.

The brackets 33 and 34 each have one wing 36 provided with a threaded aperture, as 42, which is adapted to be engaged by the threaded end of a screw 43. These screws 43 form pivots for bell-crank levers 44, and these levers may be connected to arms 45 of a universal bar, the latter being operated by the key-operated levers and the space levers in the usual way. The bell-crank levers 44 are adapted to operate a rocking or movable member which in turn serves to impart movement to the escapement and ribbon operating mechanisms, but as such features form no part of the present invention, they are neither illustrated nor described.

From the foregoing, it will be manifest that simple and efficient means is provided whereby a part of the platen shift mecha-

nism is properly guided; that said guiding means is simple in construction and forms effective means for bracing the frame and for guiding parts of the platen shift mechanism; and that simple means is provided whereby a two-part foldable support may have its members properly adjusted and rigidly held in such adjusted position to adapted the support to fold properly and freely.

Having thus described my invention, I claim as new and desire to secure by Letters Patent:

1. In a typewriting machine, the combination of a support having a pair of arms, a carriage adapted to travel along said support, brackets having openings of relatively different sizes, slides passing through the openings of the brackets and connected to the arms, means for adjusting the slides and arms in the direction of travel of the carriage, and means for moving said slides.

2. In a typewriting machine, the combination of a support, a carriage adapted to travel along said support, a bracket having an opening, a second bracket spaced from the first-mentioned bracket and provided with an elongated opening, slides passing through the openings of the brackets, and means for adjusting the slides in the direction of travel of the carriage.

3. In a typewriting machine, the combination of a frame, a support, a carriage adapted to travel along said support, a bracket having a round opening and secured to the frame at the rear corner thereof, a second bracket having an elongated opening extending in the direction of travel of the carriage and secured at the other rear corner of the frame, slides passing through the openings of the brackets and connected to the support, and means for adjusting the slides in the direction of travel of the carriage.

4. In a typewriting machine, a pair of brackets formed of sheet metal and each comprising a vertically arranged portion adapted to be secured to the frame of the machine, wings arranged at an angle with respect to said vertically arranged portion, and an overhanging guiding portion horizontally arranged and supported by the wings and each horizontal portion being provided with an opening, and slides movable in said openings.

5. In a typewriting machine, the combination of a support, slides connected to the support, a plurality of brackets formed of sheet metal and each comprising a portion adapted to be secured to the frame of the machine, and a single angular portion, each angular portion being provided with an opening forming a guide for a slide, and means for adjusting the support and slides.

6. In a typewriting machine, a support,

a sheet metal bracket having an overhanging portion and angular supporting wings, said overhanging portion being provided with a guiding opening, and a slide connected to the support and movable in said opening.

7. In a typewriting machine, the combination of a support, and sheet metal brackets each comprising a vertically arranged portion adapted to be secured to the frame of the machine, wings arranged at an angle with respect to said vertically arranged portion and an overhanging horizontally arranged portion, and means connected to the support and guided in the brackets.

8. In a typewriting machine, a bracket formed of sheet metal and comprising a portion adapted to be secured to the frame of the machine, wings arranged at an angle with respect to said portion and an overhanging and angular portion engaging the wings, said angular portion being provided with guiding means, and a slide guided by the bracket.

9. In a typewriting machine, the combination of a carriage, a frame, a support for the carriage movable above the frame, and brackets secured to the upper rear corners of the frame and each having an overhanging portion provided with an opening one longer than the other, and means connected to the support and guided in said openings.

10. In a typewriting machine, the combination of a support having a plurality of arms, a carriage mounted to move along said support, a platen mounted in the carriage, two movable slides located at opposite sides of the machine and connected to move the platen, a rod located at the lower part of the machine and rigidly holding the slides spaced apart, a second rod located at the upper part of the machine and connecting certain of the arms together, one end of said rod being provided with a threaded recess and at the end being exteriorly threaded and slotted, an internally threaded sleeve engaging the threaded end of the rod and adjustable lengthwise thereof, and screws engaging the threaded openings of the rod and adapted to adjustably hold the arms and slides apart.

11. In a typewriting machine, the combination of a support, a carriage mounted to move along said support, a platen mounted in the carriage, two movable slides located at opposite sides of the machine and connected to move the platen, a rod located at the lower part of the machine and rigidly holding the slides spaced apart, a second rod located at the upper part of the machine and having means connecting the slides together, and an adjustable sleeve on one end of the second rod for separating the slides.

12. In a typewriting machine, the combination of a support having a plurality of

- arms, a carriage mounted to move along said support, a platen mounted in the carriage, two movable slides located at opposite sides of the machine and connected to move the platen, a rod located at the upper part of the machine and having means connecting the slides together, and means for lengthening or shortening said rod.
13. In a typewriting machine, the combination of a support having a plurality of arms, a carriage mounted to move along said support, a platen mounted in the carriage, two movable slides located at opposite sides of the machine and connected to two of the arms, a rod located at the upper part of the machine and having means connecting two of the arms together, one end of said rod being provided with a recess or opening and at the other end being exteriorly threaded and slotted and provided with a threaded opening, an internally threaded sleeve engaging the threaded end of the rod and adjustable lengthwise thereof, and screws passing through the arms and engaging the threaded openings in the ends of said rod.
14. In a typewriting machine, the combination of a support, a carriage mounted to move along said support, a platen mounted in the carriage, two movable slides located at opposite sides of the machine and connected to move the platen, rods located at the upper and lower part of the machine and rigidly holding the slides spaced apart and forming therewith a substantially rigid frame, one of said rods being provided with an adjustable end, and means for moving the slides.
15. In a typewriting machine, the combination of a support, a carriage mounted to move along said support, a platen mounted
- in the carriage, two movable slides located at opposite sides of the machine and connected to move the platen, and rods located at the upper and lower part of the machine, rigidly holding the slides spaced apart, forming therewith a substantially rigid and rectangular frame, said upper rod having an adjustable sleeve at one end thereof, and means for moving the slides.
16. In a typewriting machine, the combination of a support, a carriage mounted to move along said support, a platen mounted in the carriage, two vertically movable slides located at opposite sides of the machine and connected to move the platen, and rods located at the upper and lower part of the machine, rigidly holding the slides apart and forming therewith a rigid frame, one of said rods being adjustable, brackets located at the rear corners of the machine through which the slides pass, and means for moving the slides.
17. In a typewriting machine, the combination of a two part foldable support, each part comprising two arms, means for holding the arms in pairs, a carriage adapted to travel along the support and foldable with one part thereof, brackets having openings therein, slides passing through and guided in the openings of the brackets, means for moving the slides, and means whereby the arms of one part of the support may be spread apart.

This specification signed and witnessed this 29th day of January A. D. 1913.

OTTO PETERMANN.
